US00D854336S

(12) **United States Design Patent** (10) **Patent No.:** **US D854,336 S**
(45) **Date of Patent:** ** *Jul. 23, 2019

(54) **TOOTHBRUSH**

(71) Applicant: **The Gillette Company LLC**, Boston, MA (US)

(72) Inventors: **Christine Hielscher**, Frankfurt (DE); **Sarah Mote**, Frankfurt (DE); **Dominik Langhammer**, Frankfurt (DE); **Tilmann Winkler**, Kronberg (DE); **Aycan Senturk-Andersson**, Frankfurt (DE); **Benedikt Heil**, Friedberg (DE)

(73) Assignee: **THE GILLETTE COMPANY LLC**, Boston, MA (US)

(*) Notice: This patent is subject to a terminal disclaimer.

(**) Term: **15 Years**

(21) Appl. No.: **29/618,565**

(22) Filed: **Sep. 21, 2017**

(30) **Foreign Application Priority Data**

Mar. 22, 2017 (WO) 2823801

(51) **LOC (11) Cl.** **04-02**

(52) **U.S. Cl.**

USPC **D4/104**

(58) **Field of Classification Search**

USPC D4/104, 105, 106, 107, 108, 109, 110, D4/111, 112, 113, 114, 115, 116, 117, D4/118, 121, 122, 123, 134, 135, 126, D4/127, 128, 129, 101

CPC A46B 9/04; A46B 15/0081; A46B 2200/1066; A46B 2200/1073; A46B 9/02

(57) **CLAIM**

The ornamental design for a toothbrush, as shown and described.

DESCRIPTION

FIG. 1 is a perspective view of a toothbrush;
FIG. 2 is a front elevation view thereof;
FIG. 3 is a right side elevation view thereof;
FIG. 4 is a rear elevation view thereof;
FIG. 5 is a left side elevation view thereof;
FIG. 6 is a top plan view thereof; and,
FIG. 7 is a bottom plan view thereof.

1 Claim, 2 Drawing Sheets
